UNITED STATES PATENT OFFICE.

HERVEY R. KUMLER AND CARROLL F. KUMLER, OF LOS ANGELES, CALIFORNIA.

BOX-NAILING MACHINE.

Application filed December 4, 1924. Serial No. 753,873.

To all whom it may concern:

Be it known that we, HERVEY R. KUMLER and CARROLL F. KUMLER, citizens of the United States, residing at Los Angeles, in 5 the county of Los Angeles and State of California, have invented a new and useful Box-Nailing Machine, of which the following is a specification.

This invention relates to devices for assembling and nailing boxes.

One of the objects of this invention is to provide a device or machine in which the different nailing mechanism are operated by individual electric motors.

Another object is to provide a plurality of individually operated nailing units suspended at their upper ends in a common main frame so that the lower ends of the different nailing units can be moved in any 20 direction away from their center line of gravity.

Another object is to provide a plurality of individually operated nailing units suspended within the main frame, embodying 25 controlling mechanism by which the lower free ends can be controlled in certain positions in relation to the work to be performed.

Another object is to provide a threaded stem or spindle on an electric motor by 30 which a nailing mechanism can be forced downwardly when operatively engaged with the threaded spindle of such electric motor.

Another object is to provide a plurality of nailers within a nailing unit by which 35 several nails may be driven by one operation of such unit.

Another object is to provide mechanism by which several nailers in a unit can be controlled in certain spaced relation to one 40 another, so that nails may be driven by such a unit with various spaces between the nails.

Another object is to provide mechanism by which nails can be automatically placed 45 with varying spacing, by one and the same nailing unit during the operation with a nailing machine.

Another object is to provide a nail-feeding mechanism by which various nails may 50 be used in the different nailers of a nailing unit during a continuous operation of a nailing machine.

Another object is to provide several

nailers in one unit embodying means by which any of the nailers in the unit may be 55 moved to and held in neutral, inoperative, or not-nailing position, while other nailers in the unit perform regular nailing actions.

Other objects will appear from the following description and appended claims, as 60 well as from the accompanying drawings, in which—

Fig. 1 is a fragmentary detail vertical mid-sectional view of a nailing tube.

Fig. 2 is a horizontal section through the 65 nailing tube on line 2—2 of Fig. 1.

Fig. 3 is a fragmentary detail vertical section similar to Fig. 1, in which the nailing tube is in a somewhat advanced downward position to illustrate the nail-selecting action 70 of this tube in relation to the nail-slide.

Fig. 4 is a top plan view of the nailing tube.

Fig. 5 is a fragmentary vertical cross-section on line 5—5 of Figs. 1 and 2. 75

Fig. 6 is a fragmentary vertical section on line 6—6 of Figs. 1 and 2.

Fig. 7 is a fragmentary vertical section through the nailing tube on line 7—7 of Figs. 2, 3 and 9. 80

Fig. 8 is a fragmentary side elevation of the nailing tube as seen in the direction of the arrow 8 in Fig. 9.

Fig. 9 is a horizontal cross-section through the nailing tube on line 9—9 of Figs. 3, 7 85 and 8.

Fig. 10 is a fragmentary vertical mid-sectional view through a nailing unit, illustrating the nailers in inoperative position.

Fig. 11 is a fragmentary side elevation of 90 the nailing unit in Fig. 10.

Fig. 12 is a side elevation of a nailing unit, partly in section, illustrating the nailers in actuated position.

Fig. 13 is a top plan view of a pair of engaging jaws for actuating the nailing unit when operatively engaged with the spindle of an electric motor. 95

Fig. 14 is a fragmentary diagrammatic illustration of an assembly of two nailing units in a frame structure with operating connections. 100

Fig. 15 is a fragmentary perspective view of a control for the several nailers in a nailing unit. 105

Fig. 16 is a fragmentary top plan view of

three nailers in a unit, illustrating the side-wise spacing of the different nailers in a unit.

Fig. 17 is a fragmentary side elevation 5 of the upper end of a nailer, illustrating a slight modification of suspensibly supporting a nailing unit.

Fig. 18 is a cross-section on line 18—18 of Fig. 17.

10 Fig. 19 is a fragmentary perspective view of several boards nailed together, illustrating three nails in a narrow board arranged closely together, and another three nails in a wider board spaced to quite an extent, and 15 showing also a corner-piece between two side boards in which three single nails are indicated in off-set position.

Fig. 20 is a side elevation of a hook to engage with the notches of the nailer-head 20 illustrated in Fig. 4, serving also to hold the nailers down against the tension of the springs 53 illustrated in Figs. 10 and 12.

Fig. 21 is a fragmentary front elevation 25 of a slightly modified arrangement of the operating levers and bars in connection with a nailer and a nail-box with other controlling means.

Fig. 22 is a fragmentary perspective view 30 of engaging and controlling mechanism for turning the different nailers for different positions to receive different nails, and serving to hold the nailers and other mechanism down against the tension of the springs 53 illustrated in Figs. 10 and 12, being a slightly modified form over controlling means 35 illustrated in Figs. 1, 2, 4, 15 and 20.

To facilitate a shipping of fruit, vegetables, and the like, it has been found necessary to provide certain types and shapes 40 of boxes for certain articles to avoid a damaging of such fruit and the like during transportation.

Some boxes are closed on all sides. Other boxes have end-boards and on all other sides 45 only slats. Still other boxes have cleats nailed over the top or on the bottom to space the boxes when arranged one on top of the other.

The different side-boards, slats, or spacing cleats, of such different boxes are quite 50 commonly of very much varying thicknesses. The nails used in building up these boxes must therefore quite frequently be of different lengths in one and the same box, to assure a proper holding together of the box 55 when such nails are forced through the several boards and slats and cleats of different thicknesses.

A nailing machine or apparatus, to be 60 really useful, must therefore be designed to allow the use of different nails during one and the same action.

Nails are furthermore not always in a straight line along the edge of boxes, as for 65 instance, illustrated in Fig. 19, where a cor-

ner-piece 25 is disposed between the boards 26 and 27. A nail may be forced into the board 26 so as to be in alignment with other nails in the same board at a point indicated at 28, but it is desirable to have another nail forced into the board 27 at a point indicated at 29, and eventually another nail into the corner-piece 25 indicated at 30, these three nails at the points 28, 29 and 30 being eventually forced through another slat or 75 top or bottom board to firmly hold such a corner together. To accomplish such an off-setting, a nailing machine or apparatus must be designed to allow a slight shifting 80 of the nailers to bring nails to such off-set 85 positions.

A proportionally narrow slat or board is indicated at 31 in Fig. 19, in which the positions of three nails are indicated at 32. Another somewhat wider board is indicated 85 at 33, having also the positions of three nails indicated as at 34. To accomplish such different spacing as illustrated at 32 and 34, a nailing machine must be designed to allow a quick changing of the spaces in so-called 90 gang-nailing.

Boxes are made of so many different sizes and shapes and nails are driven into various 95 positions in relation to one another that a nailing machine, to be really useful for efficient service, must allow a varying and changing and setting to quite an extent during one and the same operation on certain types of boxes, as will easily be understood 100 from the above with reference to Fig. 19.

A nailing unit of very effective and efficient design is illustrated in Figs. 10, 11 and 12. Such a nailing unit is preferably provided with an individual motor right on top 105 of the nailing unit, as indicated at 35.

In the majority of boxes, nails are driven in two parallel lines along the opposite edges of a box. Two nailing units are, for such 110 majority of boxes, sufficient in a nailing machine. Such nailing units are then preferably arranged near the two end standards 36 of a nailing machine, as illustrated in Fig. 14, a nailing unit being indicated near the opposite standards 36 at 37.

The nailing units, as illustrated in Figs. 115 10, 11 and 12, are provided with three separate and distinct nailers, as indicated at 38. More or less nailers may, of course, be used in one unit.

The motor 35, on top of each unit, is provided with a downwardly extending threaded shaft or spindle 39. The nailers of a nailing unit are suspended from a cross-head 40. Threaded blocks 41 are disposed in the cross-head 40. These threaded blocks 41 are shiftable radially in relation to the spindle 39.

In Fig. 13, a pair of threaded blocks are illustrated in top plan view. The center-most terminations 42 of the threaded blocks 130

41, are provided with threaded faces to engage with the spindle 39. Cams 43 are provided within the blocks 41, by which the threaded faces 42 may be forced into engagement with the spindle 39.

In Fig. 10 the threaded blocks 41 are illustrated in disengaged position, free from engagement with the spindle 39. An actuating member 44 is provided with notches 45 to engage with the cams 43 of the blocks 41. In inoperative position, the cams 43 are located within the notches 45 of the actuating members, so that the blocks 41 may move outwardly away from the spindle, as illustrated in Fig. 10.

When the actuating member is moved away from this inoperative position, the cams 43 are forced centrally towards the spindle, so as to engage operatively with the spindle, as illustrated in Fig. 12.

When the threaded blocks 41 are in their center-most or operative position, the turning spindle 39 forces the threaded blocks, and therewith the cross-head 40 with the suspended nailers 38, in a downward direction.

The motors 35 on the several nailing units of a nailing machine of this type are preferably operated in a continuous manner when in use, so that the cross-head with the nailers can be made to move downwardly by the mere engagement of the threaded blocks with the spindle.

A moving of the actuating member 44 produces therefore an actuating of the nailers in a unit.

To stop the movement of a nailer, or of nailers, in a unit, the actuating member 44 has merely to be brought back to normal inoperative position, so that the threaded blocks may move outwardly away from the threaded spindle, with the cams 43 resting in the notches 45 of the actuating member.

Springs 46 are provided for the threaded blocks by which the threaded blocks will be moved outwardly as soon as and whenever the cams 43 come into or are in alignment with the notches 45.

As illustrated, the actuating member 44 is forced downwardly by bars 47 to bring the actuating member into operative position, while the actuating member is automatically moved back to normal position when the nail drivers have driven the nails. The nailers when stopped in their downward movement, stop the downward moving actuating member 44, so that the still further downwardly moving cross-head with the threaded blocks tends to cause a disengagement of the threaded blocks from the spindle 39, as soon as the cams 43 reach a point to come into alignment with the notches 45 of the stopped actuating member 44.

Whenever the actuating member 44 is forced downwardly by the bars 47 to a position as illustrated in Fig. 12, the threaded blocks 41 with the cross-head 40 and suspended nailers 38, move downwardly until the nailers reach the object on which nails are to be used.

Such a condition is illustrated in Fig. 12. The line 48 may illustrate the top surface of a box. The nailers in this illustration are shown as resting on the top of the box.

As stated, the nailers are merely suspended on the cross-head 40. In the drawing, this is accomplished by a U-shaped member 49. The upright portions 50 of the U-shaped member 49 are freely shiftable through the bottom flange 51 of the cross-head 40, so that the portions 50 may move through the flange 51 when the nailers come to a stop while the cross-head is still moving downwardly on the spindle 39.

As the cross-head 40 moves downwardly, while the nailers with the U-shaped member 49 and uprights 50 have come to a stop, the downward-pointing ends 52 of the actuating member 44 come into contact with the upright ends 50, so that the actuating member 44 may be stopped in its downward movement thereby causing a neutralizing or disengagement of the threaded blocks 41 in relation to the spindle 39, as described above.

Whenever the threaded blocks are disengaged from the spindle 39, the whole cross-head with the suspended nailers, as a unit, is moved upwardly by the force of the springs 53. Springs 53 are disposed on the bolts 54 below the lower flanges 51 of the cross-head 40. The upper ends 55 of the bolts 54 are suspended from the stationary block 56, on which the motor 35 is mounted. The lower ends 57 of the bolts 54 support the guiding block 58 for the several nailers 38. The guiding block 58 is therefore somewhat stationary in this structure. The spring 53 is disposed between this relatively stationary guiding block 58 and the shiftable and movable cross-head 40.

The upper block 56, above-called stationary block, forms so to say the base for the whole structure of a nailing unit, being in fact, however, only relatively stationary with reference to the different moving parts in the nailing unit.

This block 56 is swingably and pivotally supported on the cross-head 59 of the main frame structure of the nailing machine as illustrated in Fig. 14.

The pivot connection or support for each nailing unit is preferably made as flexible as possible, that is, so that it may allow a turning movement to some extent axially, and so as to allow a swinging movement back and forth between the front and rear of the nailing machine and also a swinging

in a sidewise direction. Two nailing units are shown suspended from the cross-head 59 in the main frame structure. Of course more or less nailing units may be suspended 5 from such a cross-head depending on the requirements in nailing actions with different boxes. The several nailing units may be supported from different points in the cross-head 59, such points being indicated 10 at 60 in Fig. 14.

In Figs. 10, 11, and 12, the main cross-head 59 is illustrated in form of two bars. The bolts 61 serve to swingably support the block 56 on the main cross-head 59.

15 A slightly modified form of connection is illustrated in Figs. 17 and 18. The block designated by the numeral 56_a in this slightly modified form is provided with an annularly grooved neck 62. Fulcrum blocks 20 63 are disposed in this grooved neck 62, which are pivotally secured to the main cross-head 59 by the bolts 61. With this slightly modified form, the block 56_a, and therewith a whole nailing unit, may be 25 turned around its axis, and swing around the pivot 61 in sidewise direction between the main standards 36.

The main cross-head is provided with pins 64 in its terminations by which the cross-head 30 and therewith the whole nailing unit may be swung back and forth between the front and rear of the whole nailing machine, the pivots being indicated at 64 in Figs. 11 and 14.

35 Each nailer in a nailing unit is provided with nail-supplying and feeding means, nail-separating means, and a nailing plunger. These main parts of a nailer are illustrated in detail in Figs. 1, 2 and 3. The 40 nail-supplying and setting means of a nailer consists of an inclined block 65 with guide-plates 66 provided along the opposite sides of the block 65, so as to form spaces 67 for nails to slide towards nail-separating 45 points 68. The upper edges of the guide-plates 66 are provided with an off-set 69 by which nails are caused to assume a suitably inclined position as indicated in dotted lines at 70 in Fig. 3, so that a nail-separator can easily move in between such an advanced nail and the next following. Such an advanced nail is separated and allowed to drop into the nailing-tube 71 during the upward movement of the nailing-tube. The nailing-tube 55 is provided with a separating member 72, and just above the separating member, with an opening 73.

60 As illustrated in Fig. 3, in its upward movement, the hole or opening 73 in the nailing-tube 71, approaches the advanced nail at 72 first, so that the advanced nail is free to swing further forward with its point in the direction towards the nailing-tube, that is, into the opening 73. This action

facilitates a separating of the nails, in particular a separating of the advanced nail from the rest, so that the separating member 72 easily moves behind the advanced nail in its upward movement.

65 The advanced and separated nail easily drops into the nailing-tube as the opening of the nailing-tube moves further and further upwardly past the position in which the advanced nail was resting, until the nailing-tube 71 reaches about the position as illustrated in Fig. 1. In this normal inoperative position, the separating member 72 is located so that no more nails can pass into the nailing-tube, one nail being shown within the nailing-tube at 74 ready for the nailing action.

70 On moving downwardly, the nailing-tube passes the point where the heads of the nails tend to advance first, before the separating member 72 frees the nails in the nail-guides 75 65 for advancement, the nailing-tube tending to shut off a passing of nails from the nail-guide 65 into the nailing-tube as indicated at 75 in Fig. 3.

A plunger 76, illustrated in Fig. 1, is 90 provided to drive the nail 74 out of the nailing-tube at a proper time, as will be more fully described hereafter.

95 A guiding member 77 is provided on the nail-guide 65 in which the nailing-tube 71 may move up and down as described above. In Fig. 2, the nail-guide is illustrated as having two nail-guiding spaces 67. More or less such guiding spaces for nails can, 100 of course, be provided for each nailing-tube. The nailing-tube is disposed turnably within the guiding member 77, so that the opening 73 and the nail-separating member 72 can move up and down in suitable relation to any of such nail-guiding spaces.

105 In Fig. 2 the nailing-tube is shown in neutral inoperative position, the nail-separating member 72 being disposed in a blank groove between the two nail-guiding spaces 67, so that on an up and down moving of the nailing-tube no nail can pass from either of the nail-guiding spaces through the opening 73 into the nailing-tube 71 when the nailing-tube is so disposed.

110 A yielding engagement is provided between the nailing-tube 71 and the guiding member 77 indicated at 78 in Figs. 1 and 2. The spring-supported yielding key or plug 78 may engage with any of the grooves 79 to guide the tube in a certain relation to the nail-supplying guides of the block 65. This yielding engagement, however, can easily be overcome by a suitable turning of the tube 71. The head 80 of the tube 71 is provided with suitable notches 81, illustrated 115 in Fig. 4, by which suitable mechanism may be applied for turning the tube. If not forcefully turned, the tube 71 is normally 120 125

guided in one of the grooves 79 to bring the opening 73 and the nail-separating member 72 into alignment with a desired nail-guiding space in the nail-supplying block 65 or 5 with the neutral groove 82 illustrated in Fig. 2.

The rear end 83 of the block 65, illustrated in Figs. 1 and 2, is preferably pivotally supported in the frame 84, illustrated in Fig. 10 15, at any one of the points indicated at 85. Any desired number of nailers may be combined into a nailing unit within such a frame 84, three nailing-tubes being roughly outlined at 71 in Fig. 15, but it will easily be 15 understood that more or less nailing-tubes and therewith complete nailers can be disposed in such a frame. In Fig. 16, three 20 complete nailers are outlined as indicated at 86, pivotally supported on the bar 87 of the frame 84, in Fig. 15.

The outer-most nailers in a unit can be swung around their pivots to the positions indicated in dotted lines at 88 in Fig. 16, so that the nailers in a unit may be operated 25 with various spaces between the different nailers.

Spacing bars 89 are provided for controlling the spacing actions of the nailing-ends of the nailers in a unit. Wedge members 90 30 are provided for forcing the spacing bars 89 apart, and springs 91 are provided for bringing the nails back to and for holding the nailing members in their normal closest position in relation to one another.

Nail containers 92 are pivotally connected 35 at 93 to the nail-guides 65, as illustrated in Fig. 14, through the connections 93. The nail containers are connected with the actuating rod 47, so that a suitable shaking 40 of the containers 92 is accomplished on each actuating of the rod 47.

The rods 47 are held in their upper normal and inoperative position by the springs 94.

The bars 89 are provided with suitable 45 perforations or slots 95 for pins by which the lower free ends of the nailing units may be limited in their swinging movements. A spring 96 is illustrated by which oppositely 50 arranged nailing units may be held against swinging movements, when so resting against pins in the perforations or slots 95 of the bar 89.

The several mechanisms in this nailing 55 machine may be actuated by foot pedals or levers not shown in the drawing, through several independent or interconnected connections or connecting rods. Since principally for pulling actions, the connections may easily be of flexible material as, for instance, of wire cables or other similar suitable material.

The connections 97 are provided for moving 60 the nailing units outwardly against the tension of the spring 96, so that a so-called

gang-nailing may be accomplished along the two opposite edges of a box with slightly varying spacing from the edge of the box or between the oppositely arranged nailing units during the continuous nailing operation in connection with such a box. This arrangement allows a quick changing of 70 the position of the nailing units during the operation.

Considering the possibilities of neutralizing any movement of the nailers in a unit, it must also be understood that from a gang-nailing along the edges of the box, the machine can thus quickly be changed to single off-set nailing indicated at 28, 29 and 80 30, in Fig. 19, during the continuous normal operation of this machine.

The connections 98 are provided for actuating the wedges 90 for spacing operations 85 of the bars 89.

The connections 99 are provided for actuating the bars 47, and thereby the nailing units for the nailing actions, and incidently actuating the nail containers.

As stated above, the several nailers 38 are 90 suspended from the lower flange 51 of the shiftable cross-head 40, and the upright portions 50 of the supporting member 49 extend shiftable through the lower flange of the cross-head 40. There are certain abutments 95 in the form of nuts or flanges 100 on the upper ends of the upright portions 50 resting on the top surface of the flange 51, by which the nailers 38 are supported when so suspended from the cross-head 40.

The plunger-stems 76 of the several nailers are provided with heads 101, by which these plungers are suspended from the lower flange 51 of the cross-head 40. These heads 101 are illustrated in Fig. 1 with beveled 105 edges 102, but may as well have squarely cut edges as long as such edges allow a shifting in corresponding members or flanges 103 on the under side of the flange 51 of the cross-head 40, such flanges being indicated 110 in Figs. 10 and 12.

The heads 101 must be shiftable in the under side of the flange 51 for the reason that the nailers are also shiftable suspended to allow a variation in the spacing of the outer-most nailers by the bars 89, as described above.

The nailing-tubes 71 are provided with abutting shoulders as indicated at 104 in Figs. 1 and 10, to be shiftable within the 120 slot 105 in the U-like supporting member 49.

This double abutment in the upper ends of the nailing tubes 71 is necessary for the reason that one abutment serves to lift the nailing-tubes when suspended from the member 49, while the other abutment serves to support the member 49 with its uprights 125 50 whenever the nailers come to rest on the material on which nails are used.

When the nailers come to a stop in their 130

downward movement, as described above, bringing also the member 40 with its uprights to a stop, the cross-head 40 moves still further downwardly with the actuating member 44 and the downwardly extending ends 52.

As illustrated in Fig. 12, there is still a space between the downwardly projecting ends 52 of the actuating member 44 and the upper ends 100 of the supporting member 49 when the nailers have come to rest on the material.

It will be noticed that in this condition, the plungers are not moved into the nailing-tubes.

As the cross-head moves still further downwardly, the plungers go into the nailing-tubes of the nailers 38, thereby performing the nailing action as described above, until the ends 52 of the actuating members 44 come into contact with the then upper ends 100 of the supporting member 49.

As the nailing plungers 76 complete their nailing action when moving so downwardly into the nailing-tube, the upper ends 100 of the supporting member 49 serve to disengage the threaded blocks 41 from the motor spindle 39, as the lower ends 52 of the actuating member 44 are stopped in their downward movement by the upper ends 100 of the supporting member 49.

The threaded blocks, and therewith the whole nailing unit, is automatically disengaged from the continuously rotating motor spindle 39 on each completion of a nailing action of the nailers as described above.

As the cross-head 40, with one or more nailers in a unit, approaches its upper-most position, the actuating member 44 will come into contact with the bars 47 if the same are in depressed position. When such a contact is made the downwardly extending ends 52 are forced into the upper end of the cross-head, so as to again move the threaded blocks inwardly or centrally into closed position. The spindle is threaded from its free end upwardly to a point indicated at 106, this being a point below the threaded blocks in their upper-most position.

To start the downward movement of the nailing unit by the threaded blocks 41, the cross-head 40 with the suspended unit of nailers is suitably pressed downward to such an extent that the threaded blocks will be moved into engagement with the threaded portion of the spindle at the point 106.

A continuous nailing with automatically repeated downward actions may be accomplished by a setting of the rods or bars 47 in a depressed position so that the threaded blocks will engage the threaded portion of the spindle every time the cross-head 40 reaches its upper-most position on the spindle.

The slightly modified form of controlling

mechanism between the nailers on the one side, and the guiding box 53 and supporting member 49 on the other side, in conjunction with the springs 53, is illustrated in Fig. 22. While in the form illustrated in Figs. 1, 2, 4, 15 and 20, the hook-like member 109, illustrated in Fig. 20, is designed to engage with the notches 81 of the head 80 of the nailers, a pin 113 is provided on the top head of each of the nailers in the slightly modified form illustrated in Fig. 22. The operation of the hooks 109 in conjunction with the notches 81 may easily be understood from the description of the mechanism illustrated in Fig. 22.

As stated above, the nailers are turnably disposed in the guiding block 77 and so controlled that nails of different sizes or different types may be supplied through the opening 73 of the nailers by setting or turning the nailers to the different positions as described with reference to the illustration in Fig. 2.

Such a turning can, of course, be accomplished just as well by actuating the nailers through the pins 113, as illustrated in Fig. 22. The shaft 107 is turnably and shiftably journaled at 115. Engaging fingers 116 are adjustably mounted on the shaft 107. The shaft 107 is therefore threaded as indicated at 107_a to allow a sidewise adjustment in relation to the vertical axes of the nailers, longitudinally on the shaft 107.

A shifting of the shaft 107 in axial direction causes a turning of the nailers by the pin 113 since the pin 113 is disposed between a pair of fingers 116.

A similar result can be accomplished with the hooks 109 if disposed on the shaft 107 substituted for the fingers 116 so that the hooks may engage with any one of the notches 81 in the head 80, as illustrated in Fig. 4.

While the hooks 109, illustrated in Fig. 20, serve at the same time to also hold down the member 49 on which the nailers are suspended, in the modified form illustrated in Fig. 22 extra hooks 117 are provided to hold the supporting member 49 down while the engaging or actuating fingers 116 produce a turning movement of the nailers only.

The shaft 107 is turnably mounted to allow a disengaging of the hooks 109 or the hooks 117 from the supporting member 49, with the form illustrated in Figs. 15 and 20.

A turning of the shaft 107 serves to bring the hooks 109 into engagement with the notches 81 as well as to engage over the supporting member 49, while a turning of the shaft 107 in the slightly modified form illustrated in Fig. 22 serves to bring the hooks 117 into engagement over the supporting member 49 by the cams 118 on the shaft 107, the engaging and actuating fingers 116 at the same time engaging over the fingers

113 of the nailers. A lever 108 is provided to actuate the shaft 107. The actuating of the shaft 107 may be fully manual or a spring 119 may be provided to help in disengaging and normally holding the hooks and thereby the shaft with the engaging and actuating fingers 116 in normal inoperative position in relation to the nailers and nail-supporting members 49.

10 The spindle 39 is made to extend into the hollow of the cross-head 40 for lubricating this spindle. The cross-head is maintained full of the lubricant so that the spindle is continuously lubricated by returning to normal position within the cross-head.

Having thus described our invention, we claim:

1. In a nailing machine of the class described, nailers disposed for back and forth movements, an actuating motor having a threaded spindle, and a nailing unit carrying said nailers having means for engaging the spindle during a nailing action and adapted for disengagement from the threaded spindle on completion of the nailing action.

2. In a nailing machine of the class described, a plurality of individually electrically motor-driven nailing mechanisms, a main frame structure, means for freely suspending said nailing mechanism within the main frame structure, and means for controlling the position of the lower free ends of the mechanisms in the main frame structure.

3. In a nailing machine of the class described, a frame structure, a plurality of nailing mechanisms suspended from the frame structure, each nailing mechanism consisting of several nailers, an individual motor for each of the said mechanisms, a cross-head shiftably disposed in the direction of suspension, engaging means between the said cross-head and the said motor in

45 each of the mechanisms, means for engaging the engaging means with the motor for actuating the cross-head in a downward direction adapted to release the cross-head on completion of its downward movement,

50 means for automatically returning the cross-head with the nailers to the upper-most normal and inoperative position, the several nailers in a mechanism including nail holders suspended from the said cross-head by means adapted to allow a downward movement of the cross-head while the suspended nail holders have come to a stop, and nailing plunger suspended from the cross-head adapted to move into the nail holders when the nail holders come to a stop while the cross-head is still moving downwardly.

60 4. In a nailing machine of the class described, a frame structure, a plurality of nailing mechanisms suspended from the

frame structure, each nailing mechanism 65 consisting of several nailers, an individual motor for each of the said mechanisms, a cross-head shiftably disposed in the direction of suspension, engaging means between the said cross-head and the said motor in 70 each of the mechanisms, means for engaging the engaging means with the motor for actuating the cross-head in a downward direction, means for automatically returning the cross-head with the nailers to the upper-most 75 normal and inoperative position, the several nailers in a mechanism including nail holder suspended from the said cross-head by means adapted to allow a downward movement of the cross-head while the suspended nail holders have come to a stop, nailing plunger suspended from the cross-head adapted to move into the nail holders when the nail holders come to a stop while the cross-head is still moving downwardly, 80 and means controlled by the nailers for disengaging the motor-engaging means.

5. In a nailing machine of the class described, a nailer consisting of a reciprocable nailing tube having an opening in one longitudinal side and having a nail-separating member projecting outwardly in a radial direction from the tube and extending from the opening downwardly, a nail-supplying guide having a plurality of guideways for 90 nails, the said nail-supplying guide having passageways for the said nail-separating member in relation to each of the guideways and in a neutral position so that the nailing tube with the nail-separating member may 95 pass up and down in front of the nail-guide ways as well as in an inoperative position away from the nail-supplying guideways, means for setting the nailing tube shiftable 100 within the nail-supplying guide in relation to the one of the guideways and the neutral position, and a nailing plunger disposed in the nailing tube.

6. In a nailing machine of the class described, an electric motor having a threaded spindle pointing in a downward direction, a frame structure, a nailing unit disposed in the frame structure below and in alignment with the said spindle, and means for engaging the nailing unit with the threaded spindle during a nailing action adapted to release the nailing unit to permit the same to return to normal inoperative position at the completion thereof.

7. In a nailing machine of the class described, a nailing mechanism consisting of several nailers with nail-supplying means, a supporting frame, a plurality of nail-supplying guides pivotally supported by the said frame, nailing tubes shiftably disposed in the free-swinging ends of the nail-supplying guides for movements in up and down directions, nailing plungers in each

of the nailing tubes, the axes of the several plungers being practically parallel in the several nailers to one another, and means for controlling the freely swinging ends of the nail-supplying guides so as to hold the nailers spaced in a desired relation to one another.

8. In a nailing machine, a main frame, a plurality of independent nailing mechanisms each embodying an individual electric motor and nailers actuated thereby, flexible connections suspending said mechanisms in the frame and adjustable therein, bars yieldingly supported on the main frame for guiding the lower free ends of the mechanisms and for determining the lateral spacing of the nailers, members to actuate and control said bars, and controls for governing said mechanisms in their normal operations of feeding and driving nails.

9. In a box-nailing machine, nailing mechanisms disposed for universal movements, actuating motors having threaded spindles, and nailing units having means for engaging the spindles during a nailing action and adapted to be disengaged from the threaded spindles on completion of the nailing action.

10. In a box-nailing machine, a plurality of individually electrically motor-driven nailing mechanisms, a main frame structure, and means for universally suspending nailing mechanisms within the main frame structure.

11. In a box-nailing machine, a plurality of individually electrically motor-driven nailing mechanisms, a main frame structure, means for universally suspending nailing mechanisms within the main frame structure, and means for controlling the lower freely swinging ends of the mechanisms in the main frame structure.

12. In a box-nailing machine, a frame structure, a plurality of nailing mechanisms universally suspended from the frame structure, each nailing mechanism consisting of one or more nailers, an individual motor for each of the said mechanisms, a cross-head shiftably disposed in the direction of suspension, engaging means between the said cross-head and the said motor in each of the mechanisms, means for engaging the engaging means with the motor for actuating the cross-head in a downward direction adapted to release the cross-head on completion of its downward movement, means for automatically returning the cross-head with the nailers to the upper-most normal and inoperative position, the one or more nailers in a mechanism having nail-holders suspended from the said cross-head by means adapted to allow a downward movement of the cross-head while the suspended nail-holders have come to a stop, nailing plungers suspended

from the cross-head adapted to move into the nail-holders when the nail-holders come to a stop while the cross-head is still moving downwardly, means to feed nails to the several nail-holders in a mechanism, and means to control the feeding of said nails.

13. In a box-nailing machine, a frame structure, a plurality of nailing mechanisms suspended from the frame structure, each nailing mechanism consisting of one or several nailers, an individual motor for each of the said mechanisms, a cross-head shiftably disposed in the direction of suspension, engaging means between the said cross-head and the said motor in each of the mechanisms, means for engaging the engaging means with the motor for actuating the cross-head in a downward direction, means for automatically returning the cross-head with the nailers to the upper-most normal and inoperative position, the several nailers in a mechanism having nail-holders suspended from the said cross-head by means adapted to allow a downward movement of the cross-head while the suspended nail-holders have come to a stop, nailing plungers suspended from the cross-head adapted to move into the nail-holders when the nail-holders come to a stop while the cross-head is still moving downwardly, means controlled by the nailers for disengaging the motor-engaging means, means to feed nails to the several nail holders in a mechanism, and means to control the feeding of said nails.

14. In a box-nailing machine, an electric motor having a threaded spindle pointing in a downward direction, a frame structure, a nailing unit suspended in the frame structure below and in alignment with the said spindle, and means for engaging the nailing unit with the threaded spindle during a nailing action adapted to release the nailing unit to permit the same to return to normal inoperative position.

15. In a box-nailing machine, a nailing mechanism consisting of one or more nailers, nail-supplying means, a supporting frame, a plurality of nail-tube guides pivotally supported by the said frame, nailing tubes shiftably disposed in the free-swinging ends of the nail-tube guides for movements in up and down directions, nailing plungers in each of the nailing tubes, the axes of the several plungers being practically parallel in the several nailers to one another, and means for controlling the freely swinging ends of the nail-tube guides so as to hold the nailers spaced in a desired relation to one another.

16. In a nailing machine, a main frame, a nailing mechanism universally suspended in the main frame, a cross-head shiftable within the nailing mechanism, actuating means for the cross-head, nailers suspended from

the cross-head in operative connection therewith, and interengaging means between the cross-head and the actuating means adapted to free the cross-head when the nailers contact with work.

17. In a nailing machine, a main frame, and a nailing mechanism embodying actuating and actuated means, and including nailers suspended from the actuated means, 10 interengaging means between the actuated means and the actuating means in operative connection with the nailers adapted to free the actuated means from the actuating means when the nailers contact with work, 15 and neutralizing means for returning the nailers and their supporting actuated means

upwardly when the actuated means are so freed.

18. In a nailing machine, a power-actuated cross-head or the like guided member 20 with nail-driving mechanisms attached thereto and operated thereby, means to disengage said cross-head from its actuating power during its downward movement upon contact of the nailers with the work, and 25 means to return the cross-head with the nailers to inoperative position upon such disengagement.

In testimony that we claim the foregoing as our invention we have signed our names.
